Attorney

UNITED STATES PATENT OFFICE.

ISAAC C. HOWLETT, OF BANGS, TEXAS.

TIRE-OVEN.

1,345,188.

Specification of Letters Patent. Patented June 29, 1920.

Application filed February 7, 1919. Serial No. 275,603.

To all whom it may concern:

Be it known that I, ISAAC C. HOWLETT, a citizen of the United States of America, residing at Bangs, in the county of Brown 5 and State of Texas, have invented new and useful Improvements in Tire-Ovens, of which the following is a specification.

The purpose of the invention is to provide a device for heating wagon and buggy wheel 10 tires so that the same may be evenly heated throughout. To this end the invention comprises an annular outer casing and an annular inner casing, the walls of the two being in spaced relation to each other with a series 15 of burners arranged around the outer wall of the inner casing and the inner wall of the outer casing, the burners of the one projecting their flame toward the burners of the other. Beneath the burners there are pro- 20 vided a plurality of supports on which the tire or tires may be carried and this construction provides for the heating of the tire upon the inside as well as upon the out, so that the distribution of the heat will be 25 uniform throughout. The device is de- 30 signed to be closed at the top between the inner and outer casing, so when it is in use the heat generated thereby may be confined to that part wherein the tires are carried.

The invention is illustrated and described in a specific embodiment, to which, however, it is not to be restricted. The right is re- 35 served to make such changes or alterations as the actual reduction to practice may suggest, in so far as such changes or alterations are compatible in spirit with the annexed claim.

The same numerals of reference designate the same parts throughout the several figures of the drawings, wherein:

Figure 1 is a view in side elevation of the improved device.

Fig. 2 is a top plan view.

Fig. 3 is a section on the line 3—3 of 45 Fig. 2.

Fig. 4 is a section on the line 4—4 of Fig. 2.

Referring to the drawings, there is shown an outer annular casing 1 and an inner annular casing 2, the walls of which stand in 50 spaced relation to each other. These two casings are secured together by means of radially disposed braces 3, so that the spacing of the two which is desired for effective 55 work may be maintained.

Surrounding the annular casing 2 on the

exterior there is an annular pipe or gas or fuel conducting tube 4 which is provided with outwardly disposed radially projecting burners 5. Lying in the same plane with 60 the pipe 4 there is a section pipe 6. This is also annular in shape and lies against the inner wall of the outer casing 1, being provided with the burners 7 which are radially disposed but project inwardly, so that they 65 face the burners 5 on the pipe 4. The two pipes 4 and 6 stand above the braces 3 and the latter aside from serving to hold the two casings together and in spaced relation to each other, serve also to support tires which 70 may be placed in the device.

The device is designed to use either gas, gasoline or other suitable fuel which is admitted to the pipes 4 and 6, the fuel being vaporized or carbureted in any acceptable 75 manner before admission to the pipes, being admitted to the same through a supply pipe 8 in which there is included a control valve 9, suitable tubular or pipe connections 10 and 11 leading from the valve to the pipes 80 4 and 6 respectively.

Hingedly attached at diametrically opposite sides of the casing 1, there are the cover members 12, the two being of such shape that they close the device at the top of the 85 space wherein the burners are contained, but leave open the space through the inner casing.

It is obvious that when the burners are lighted, a tire may be placed in on the supports or braces 3 when the flames from the burners will be projected against the inner and outer peripheries of the tire, thus making the distribution of heat uniform throughout so that the tire will be expanded 95 uniformly.

From the foregoing description and the accompanying drawings, it is believed that a clear enough understanding of the invention is to be had to render further description unnecessary.

The invention having been described what is claimed as new and useful is:

An oven for the purpose indicated comprising an inner annular casing, and an 105 outer annular casing, combined braces and supports radially disposed and connecting the two casings together whereby the two are held in spaced relation to each other, an annular fuel conducting pipe disposed 110 against the inner wall of the outer casing and just above the combined braces and sup-

ports, a similar annular fuel conducting pipe disposed against the outer wall of the inner casing directly opposite the first said pipe, both pipes being provided with burners radially disposed with those of the one pipe directed toward those of the other pipe whereby a tire supported on the combined braces and supports may be heated on both

its inner and outer periphery, cover members hingedly attached to the outer casing ¹⁰ and movable to and from positions of closure for the space between the two casings, and means for conducting fuel to the two said annular fuel pipes.

In testimony whereof I affix my signature. 15

ISAAC C. HOWLETT.
